UNITED STATES PATENT OFFICE.

HARRY F. SMITH, OF LEXINGTON, OHIO, ASSIGNOR, BY MESNE ASSIGNMENTS, TO THE GAS RESEARCH COMPANY, OF DAYTON, OHIO, A CORPORATION OF OHIO.

MOISTURE REGULATION.

1,397,555.

Specification of Letters Patent. Patented Nov. 22, 1921.

Application filed November 7, 1917. Serial No. 200,860.

To all whom it may concern:

Be it known that I, HARRY F. SMITH, a citizen of the United States of America, residing at Lexington, Richland county, Ohio, have invented certain new and useful Improvements in Moisture Regulation, of which the following is a full, clear, and exact description.

This invention relates to gas generation and more particularly to a method of regulating the supply of moisture to a gas generating chamber according to the character of the gas produced. And one object of the invention is to provide an effective method of regulating the supply of moisture to a gas generating chamber according to the composition, and more especially according to the heat value, of the gas produced, and to provide apparatus which is sufficiently sensitive, sufficiently accurate, and still sufficiently substantial to permit of its practical application for carrying such method into effect.

This invention is quite general in its applicability, being capable of use in connection with any form of generator in which the production of gas is so dependent upon an influx of fluid to the generating chamber that variations in such influx give rise to variations in the character of the gas produced. For purposes of clearer description, however, I have described my invention in connection with a so-called gas producer of the suction type, it being obvious, however, that it would operate in the same manner and with equal efficiency in many other relationships.

It has been the general practice, heretofore, in the gas producer art, to introduce steam along with the air in the blast, and to endeavor to maintain, during operation of a producer, some desired proportioning. The steam has a quenching effect, thus lowering the temperature of the fuel bed and tending to eliminate fusing of the ash, or clinkering, and has the further function of increasing the percentage of combustible in the generated gas. But the regulation of the moisture or steam introduced has been primarily such as to prevent excessive clinker formation. I have found that, not only is the steam useful in thus controlling the physical condition of the fuel bed, and increasing the percentage of combustible, but that the composition of the gas generated may

also be controlled by regulating the relative proportioning of air and moisture introduced into the generating chamber.

Upon the introduction of fresh fuel to the fuel bed there will be an ensuing evolution of hydrocarbons, such as methane, having a high B. T. U. value. If other conditions in the generating chamber remain the same, such evolved hydrocarbons will greatly increase the heat value of the gas as a whole. It is, however, oftentimes desirable that the heat value of the gas be kept substantially constant. Since it is very difficult to control this evolution of hydrocarbons from the fresh fuel, I control the production of ether of the constituents of the gas so as to insure a comparatively constant B. T. U. value. Such control may be readily accomplished by regulating the quantity of moisture introduced to the generating chamber, to vary the production of hydrogen. That is, if the relative proportion of any one of the heat producing constituents of the gas should increase, a gas of constant heat value may nevertheless be maintained if another heat producing constituent of the gas is correspondingly decreased in quantity. So, if, upon the addition of fresh fuel, the proportion of hydrocarbons evolved is increased, with a corresponding tendency toward increase in heat value, a corresponding decrease in the proportion of hydrogen will maintain the heat value of the gas at the desired normal. And, in my method of regulation, just such decrease in the proportion of hydrogen is secured by decreasing the relative quantity of moisture introduced into the generating chamber.

Any decrease in the relative proportion of steam or moisture in the blast is followed by the development of higher temperatures in the fuel bed. So cutting down the relative quantity of moisture to compensate for an excessive production of hydrocarbons, causes a rise in the temperature of the fuel bed. But following the excessive evolving of hydrocarbons from fresh fuel there will follow a corresponding decrease in their evolution. So the heat value of the gas would then tend to drop below the desired normal. At such time the quantity of moisture introduced is proportionately increased, the increased moisture being readily decomposed, without undue cooling of the fuel bed, because of the heat theretofore stored.

up therein, to increase the percentage of hydrogen and thus maintain the heat value normal.

Therefore, whereas, heretofore, the practice has been, for a given fuel, to endeavor to maintain constant the relative proportions of air and moisture in the blast, in the carrying out of my method the proportion of moisture in the blast is intentionally varied from time to time according to the composition of the gas generated, the regulation being such as to maintain the composition of the gas substantially uniform.

In carrying my method into effect I make use of apparatus similar to that disclosed in the drawing, which is shown partly in elevation and partly in section in order to more clearly disclose the mechanical details of construction, and in which:

26 Figure 1 is a preferred embodiment of such apparatus comprising pressure operated means for controlling the moisture regulating valve.

Fig. 2 is another preferred embodiment comprising electrically operated means for actuating the moisture controlling valve.

In the form of apparatus disclosed in Fig. 1, 1 is a gas main for conveying the gas produced in the generating chamber of the producer to any desired place of use or storage. Leading from this main is a pipe 2 for conveying away therefrom a fraction of the gas passing through the main, which fraction of gas will have the same varying constituents and pressure as the gas in the main 1. Inserted in the pipe 2 is a pressure regulating valve 3. Any desired form of pressure regulating valve may be used, in place of the form disclosed, inasmuch as the precise form thereof constitutes no part of the present invention. The pressure regulating valve shown comprises a diaphragm operated valve adapted to increase or decrease the opening through the valve seat 4 thereof to insure a constant and uniform pressure in the pipe 2 beyond such seat. Also located in the pipe 2 is a diaphragm 4, having a constant orifice 5 therein. Inasmuch as the pressure of the gas in the pipe 2 beyond the pressure regulating valve 3 is constant, thus insuring a constant pressure at the orifice 5, and inasmuch as the orifice 5 is itself constant, it is evident that the flow of gas therethrough will also be constant. Attached to the free end of the pipe 2 is a gas burner 6 of any desired form, which burner extends inside the chamber 7. The side walls of the chamber are closed excepting for certain air inlet ports 8 in the bottom thereof for supplying a sufficient quantity of air to insure complete combustion of all gas passing through the burner 6. The upper end of the chamber 7 is left open so that the heated gases, resulting from combustion of the gas passing through the pipe

2 and burner 6, will pass upwardly through the chamber 7. Located in the upper part of chamber 7, in such wise as to be acted upon by the heated gases passing therethrough, is a closed vessel 9, which preferably contains therein a volatile liquid 10, of any desired character.

Leading off from the vessel 9 is a pipe 11 which opens into the lower end of a bellows-like expansible chamber 12. Inasmuch as the flow of gas through the orifice 5 is constant under all conditions, it is evident that any variation in the heat developed at the burner 6 must result from variations in the heat value of the gas itself. And inasmuch as the entire amount of heat produced at the burner 6 passes upwardly through the chamber 7, any variations in the amount of such heat must of necessity increase or decrease the degree of vaporization of the volatile liquid in the vessel 9, to thus increase or decrease the pressure in the expansible chamber 12 with a corresponding elongation or shortening of that chamber.

Pivotedly attached to the upper end of the expansible chamber 12 is a link 13, the opposite end of which is pivotally attached to the lever 14 intermediate the ends thereof. One end of the lever 14 is fulcrumed at 15 to some stationary part of the apparatus. Pivotedly attached to the opposite end of the lever 14 is an adjustable link 16, the free end of which is operatively connected to the operating handle 17 of a valve 18. The valve 18 is located in and controls the pipe 19 which conveys moisture to the generating chamber of the gas producer. This moisture may be supplied in any desired manner, for example, in the form of steam which is passed directly into the generating chamber or into a saturator where it is taken up by the inflowing air and thus carried into the generating chamber, or of water, which passes through the pipe 19 to a saturator or to a spray nozzle located in the ash pit of the producer where it is sprayed in excess into the air flowing to the fuel bed, the amount of spray carried along by such inflowing air being dependent upon the relative quantity thereof introduced into the ash pit. The precise manner of introducing the moisture to the fuel bed is, however, a matter of indifference so far as regards this invention, and is mentioned here merely to show the general applicability of my particular method of regulation. Attached to the same end of the lever as the link 16 is a spring 20, the opposite end of which is rigidly connected to some fixed part of the apparatus. As shown this spring is attached to the pipe 19 and is adapted to normally urge the lever 14 to bring about an opening movement of the valve 18. Any increase of pressure in the expansible chamber 12 will result in an elong-

gation of that chamber to cause such movement of the lever 14, and the elements connected therewith, as will bring about a corresponding actuation of the valve 18. And conversely any decrease of pressure in the chamber 12 will in the same manner bring about a reverse movement of the valve 18.

From the above it is evident that any increase in the B. T. U. value of the gas passing through the main 1, will result in an increase of heat at the burner 6. Such increase of heat will cause an expansion of the chamber 12 to thus actuate the valve 18. And the valve 18 is so positioned that any 15 increase in pressure in the chamber 12 will cause a closing movement of such valve. Likewise any decrease in the B. T. U. value of the gas will immediately result in a decrease in the amount of heat generated at 20 the burner 6 to cause an opening movement of the valve 18.

In the form of apparatus disclosed in Fig. 2 different mechanism for actuating the valve is shown. In this form of mechanism, 25 as in that disclosed in Fig. 1, a pipe 2 leads off from the gas main 1 to the burner 6, a pressure regulating valve 3 and a constant-opening diaphragm 4 being inserted therein. Located inside the chamber 7 is a thermos- 30 static strip 21 attached to a bracket 21' which is insulated from the wall of the chamber 7 by means of any desired insulating material 22. This strip 21 is so located in the chamber 7 that it is subjected to the 35 effect of the gases heated at the burner 6. Passing through the wall of the chamber 7 are two contact elements 23 and 24 which are insulated therefrom by means of the insulating plugs 25. Of course any other de- 40 sired means of insulating the elements 23 and 24 from the chamber 7 may be em- ployed. These contact elements extend into the chamber 7 and their inner ends are located adjacent the free end of the thermo- 45 static strip 21 and upon opposite sides there- of. Any increase or decrease in the amount of heat generated at the burner 6 will cause a corresponding deformation of the thermo- static strip toward one contact element or 50 the other, the sensitiveness of the thermo- static strip and relative positioning of the two contact elements 23 and 24 being such that in actual practice a very slight deformation of the strip in either direction will 55 cause it to contact with one of these elements.

Rigidly attached to the end of the valve stem 17 are two disks 26 and 27, rotation of either of these disks causing correspond- 60 ing rotation of the valve stem to open or close the valve 18. Located between the two disks 26 and 27 and adapted to contact with either of them is a friction pulley 28 carried by the shaft 29 of the motor 30. The 65 shaft 29 has therein intermediate the motor

and the friction pulley 28, a universal joint 31. The motor 30 is adapted to rotate continuously in one direction and to impart to the friction pulley 28 a corresponding motion. Because of the universal joint in 70 the driving shaft the pulley can be urged into substantial frictional contact with either of the disks 26 or 27 and maintained in such contact therewith at all times.

Surrounding the shaft 29 between the universal joint 31 and the pulley 28 is a loosely mounted collar 32 adapted to permit of ready rotation of the shaft 29 therein. Attached to the collar 32 at diametrically opposite points are two metallic members 33 and 34. The members 33 and 34 extends inside the solenoids 35 and 36 respectively and constitute in effect cores for such solenoids. Energizing either solenoid 35 or 36 will cause axial displacement of the core co- 85 operating with such solenoid to bring the friction pulley 28 into frictional contact with one of the plates 26-27. Inasmuch as the motor 30 is rotating the friction pulley 28 continuously in one direction, it is evident 90 that bringing that pulley into substantial frictional contact with either of the disks 26-27 will cause a corresponding rotation of that disk about its axis to bring about a rotation of the valve 18. It is also evident 95 that inasmuch as the rotation of the friction pulley is constant in direction, bringing it in contact with the disk 26, will cause a rotation of the valve in a direction opposite to that caused from bringing it into contact 100 with the other disk 27.

Attached to the thermostatic strip 21 through the medium of the bracket 21', is a conductor 37, which leads to one terminal of each of the solenoids 35 and 36. Attached 105 to the contact element 23 is a conductor 38 which is connected to the other terminal of the solenoid 36. Attached to the contact element 24 is a conductor 39 which is connected to the other terminal of the solenoid 110 35. Located in the circuit connected to each of the solenoids 35 and 36 is a battery 40 adapted to energize such solenoids upon closing the circuit connected thereto. Sufficient deformation of the thermostatic strip 115 21 to contact with either of the elements 23-24 will immediately cause a closing of the circuit through the solenoid corresponding thereto to energize that solenoid, and thus bring the friction pulley into substantial frictional contact with one of the disks 120 26-27.

The operation of this device is apparent from the above description. Since the flow of gas through the orifice 5 to the burner 6 125 is constant, any variation in the heat generated at such burner must result from a variation in the heat value of the gas being burned. This variation in the amount of heat generated at the burner 6 will cause 130

4
a deformation of the thermostatic strip 21 to bring about contact thereof with one of the elements 23-24 to thus energize the corresponding solenoid and urge the friction 5 pulley into driving contact with the corresponding disk 26-27 to bring about an opening or closing movement of the valve 18. It is evident that the various elements of this apparatus can be so arranged that 10 any increase in the amount of heat generated at the burner 6, will cause such movement of pulley 28 as will bring about a decrease in the amount of moisture flowing through the pipe 19, and conversely that any decrease 15 in the amount of heat generated at the burner 6 will bring about such actuation of the valve 18 as will permit of an increased flow through the pipe 19.

While the method herein described, and 20 the forms of apparatus for carrying this method into effect, constitute preferred embodiments of the invention, it is to be understood that the invention is not limited to this precise method and these forms of apparatus, and that changes may be made in either without departing from the scope of the invention which is defined in the appended claims.

What I claim as new and desire to secure 25 by Letters Patent is:

1. The method, in the generation of gas, in which air and moisture are supplied to the gas generating chamber, means being provided for controlling the quantity of 35 moisture supplied, which consists in continuously controlling the amount of moisture according to the composition of the gas produced.

2. The method, in the generation of gas, 40 in which air and moisture are supplied to the gas generating chamber, means being provided for controlling the quantity of moisture supplied, which consists in automatically controlling the amount of moisture 45 according to the composition of the gas produced.

3. The method, in the generation of gas, in which air and moisture are supplied to the gas generating chamber, means being 50 provided for controlling the quantity of moisture supplied, which consists in continuously controlling the amount of moisture supplied according to the heat value of the gas produced.

55 4. The method, in the generation of gas, in which air and moisture are supplied to the gas generating chamber, means being provided for controlling the quantity of 60 moisture supplied, which consists in automatically controlling the amount of moisture supplied according to the heat value of the gas produced.

5. The method, in the generation of gas, 65 in which air and moisture are supplied to the gas generating chamber, means being

provided for controlling the quantity of moisture supplied, which consists in continuously withdrawing a constant quantity of the gas produced, burning the gas so withdrawn, and automatically controlling the 70 supply of moisture to accord with variations in the quantity of heat thus generated.

6. The method, in the generation of gas, 75 in which air and moisture are supplied to the gas generating chamber, means being provided for controlling the quantity of moisture supplied, which consists in continuously withdrawing a definite quantity of the gas produced and burning the gas so withdrawn in such wise as to operatively 80 effect actuating mechanism controlling the moisture supply regulating valve to vary the relative opening of said valve to accord with variations in the heat value of the burned 85 gas.

7. The method in the operation of gas producers, in which air and moisture are supplied to the generating chamber of the producer, means being provided for controlling the quantity of moisture supplied; 90 which consists in continuously withdrawing a constant quantity of the gas produced in said generator; and burning such withdrawn gas in such wise as to operatively effect heat responsive apparatus constructed 95 to actuate the moisture controlling means, to vary the quantity of moisture supplied to the generating chamber to accord with variations in the heat value of the burned gas.

8. The method, in the operation of gas 100 producers, in which air and moisture are supplied to the generating chamber of the producer, which consists in continuously controlling the quantity of moisture supplied according to the composition of the 105 gas produced, irrespective of any variation in the amount of air supplied.

9. The method, in the operation of gas 110 producers, in which air and moisture are supplied to the generating chamber of the producer, which consists in continuously controlling the quantity of moisture supplied to accord with variations in the heat 115 value of the gas produced, irrespective of any variations in the amount of air supplied.

10. Apparatus for controlling the supply 120 of moisture to a gas generator, comprising a moisture supply pipe, through which moisture is introduced into the gas generating chamber, a moisture controlling valve in said pipe, means for operating said valve; and temperature responsive means for actuating the operating means, said temperature responsive means including a thermostatic element, a burner adjacent thereto, and 125 means for supplying a constant quantity of the generated gas to said burner.

11. Apparatus for controlling the supply 130 of moisture to a gas generator, comprising a moisture supply pipe, through which mois-

ture is introduced into the gas generating chamber, a valve in said supply pipe, means for operating said valve; and means for actuating said operating means to vary the 5 opening of said valve to accord only with variations in the composition of the gas produced.

12. Apparatus for controlling the supply of moisture to a gas generator, comprising a 10 moisture supply pipe, through which moisture is introduced into the generating chamber, a moisture controlling valve in said supply pipe, means for operating said valve, and means for actuating said operating 15 means, constructed to cause the operating means to vary the opening of the valve to accord only with variations in the heat value of the gas produced.

13. Apparatus for controlling the supply 20 of moisture to the gas generating chamber of a gas producer, comprising a moisture supply pipe, through which moisture is introduced into the generating chamber, means for controlling the flow of moisture through 25 said supply pipe; and means responsive only to variations in the heat value of the generated gas for actuating said controlling means to control the moisture supplying means.

14. Apparatus for controlling the supply 30 of moisture to a gas generator, comprising a moisture supply pipe, through which moisture is introduced into the generating chamber, a moisture controlling valve in said supply pipe, means for operating said valve; and temperature responsive means for actuating 35 said operating means to vary the relative opening of said valve in accordance only with variations in the heat value of the 40 gas produced.

15. Apparatus for controlling the supply 45 of moisture to a gas generator, comprising a moisture supply pipe, through which moisture is introduced into the generating chamber, a moisture controlling valve in said

pipe; and operating mechanism for said valve, said mechanism comprising an expansible chamber, and temperature responsive means coöperating with said chamber for varying the expansion thereof to operate 50 said valve in accordance only with the heat value of the gas produced.

16. Apparatus for controlling the supply of moisture to a gas generator, comprising a moisture supply pipe, through which moisture is introduced into said generator, a moisture controlling valve in said supply pipe; an operating mechanism for said valve, comprising an expansible chamber, temperature responsive means for varying 55 the expansion of said chamber, a burner co-operating with said temperature responsive means, and means for supplying to said burner a constant quantity of the gas produced; the construction being such that the 60 operation of the moisture controlling valve is in accordance only with the heat value of the gas produced.

17. Apparatus for controlling the supply 65 of moisture to a gas generator, comprising a moisture supply pipe, through which moisture is introduced into the generator, a moisture controlling valve within said pipe, means for operating said valve; temperature responsive means for actuating said 70 operating means, said temperature responsive means including a thermostatic element, a burner adjacent the thermostatic element, a pipe connecting said burner to the gas delivery main, and means in said pipe, includ- 75 ing a pressure regulating valve and a member containing a constant orifice, for maintaining constant the quantity of gas delivered to said burner; the construction being such that the moisture controlling valve 80 is operated only in accordance with the composition of the gas produced.

In testimony whereof I affix my signature.

H. F. SMITH.
